UNITED STATES PATENT OFFICE.

HELEN S. CARSON, OF CHICAGO, ILLINOIS.

WINDOW-GUARD.

1,240,025.

Specification of Letters Patent. Patented Sept. 11, 1917.

Application filed December 19, 1916. Serial No. 137,897.

To all whom it may concern:

Be it known that I, HELEN S. CARSON, a citizen of the United States, and a resident of Chicago, in the county of Cook and 5 State of Illinois, have invented certain new and useful Improvements in Window-Guards, of which the following is a specification.

My present invention relates generally to 10 window guards, and more particularly to window guards of that nature consisting of skeleton frames inserted in position within a window frame, in the vertical plane of an outer sash and located below the same and outwardly beyond the inner sash, in order to effectually prevent ingress and egress irrespective of the position of the lower sash allowing the latter to freely move to and from closed position.

20 The primary object of my present improvements is to provide a window guard which may be readily inserted in, and removed from, its operative position in order to provide for its use in selected windows 25 of a series, and its change from one window to another, as desired.

A further object of my invention is to 30 provide a guard, the several main guard bars of which may be effectively locked in operative position by the use of a single lock, so as to necessitate the use of but a single key in securing the same in, and removing the same from, operative position.

A still further object of my invention is 35 to provide a construction susceptible to considerable range of adjustment in adapting the same to spaces of varying widths and heights, and a still further object is to provide a strong and effective arrangement permitting of practically unlimited embellishment where beauty and design and artistic qualities are a consideration, above and beyond the normal strength and efficiency of 40 the arrangement as a guard.

45 Referring now to the accompanying drawings illustrating my invention and forming a part of this specification,

Figure 1 is an elevation illustrating my improved guard in operative position.

50 Fig. 2 is an enlarged sectional view taken through the central portion of the guard substantially on the line 2-2 of Fig. 1.

Fig. 3 is a vertical transverse section taken substantially on line 3-3 of Fig. 1.

Fig. 4 is a detail section through one of 55 the socket fasteners and a portion of one of the guard bars.

Fig. 5 is an inside face view of one of the clamping plates.

Fig. 6 is a front elevation of the locking 60 screw.

Fig. 7 is a side elevation thereof.

Referring now to these figures, and particularly to Figs. 1, 3 and 4, my improved guard essentially comprises a plurality of 65 radially extending guard bars 10, each of which is threaded at 11 for some distance from its outer end, so as to adapt the same to screw within, and be adjusted with respect to, a tubular connecting member 12, 70 the outer end of which member is permanently and pivotally connected by means of a rivet 13, or the like, to an angularly projecting stud piece 14 for engagement within a socket fastening member 15. 75

As particularly seen in Figs. 1 and 4, the socket fastening members 15 are secured in a series of equal number to the guard bars 10, at the upper and lower portions of the space in which the guard is to be erected, 80 the two upper fastening members 15 being preferably secured to the lower rail 16 of the upper sash, and the two lower fastening members being secured to the sill 17, all of the fastening members 15 being in the same vertical plane, and each having fastening screws 18 extending into the material of the parts to which it is connected and projecting through its inner wall only, so that the heads of the screws or fastening members 18 will be covered, as particularly seen in Fig. 4, when the respective stud piece 14 is introduced therein, so as to thereafter prevent unwarranted removal of the socket fasteners 15, while the guard bars 10 are in 85 operative position as presently seen. 90

The inner ends of the several guard bars, clustered as they are at the center of the guard frame in operative position, are, in 100 this position clasped by a pair of opposing clamping plates 19 and 20, each of which is provided with an inwardly projecting annular flange 21 around its outer edge, the flanges 21 having grooves 22 which when together, form channels for the reception of 105 the inner ends of the bars 10, and there being several such grooves adjacent the position of each bar in order that the inclina-

tion of the several bars 10 may be varied in connection with window spaces of greater than normal width or height.

By referring to Fig. 2, it will be noted that the clamping plate 19 nearest the inside of the window space, is provided with an enlarged central opening 23, the opposing plate 20 having a central tubular extension 24 projecting toward the clamping plate 19, with its outer end closed, and with its inner end provided with an internally threaded inwardly projecting flange 25 into which the externally threaded tubular barrel 26 of a clamping nut 27 is adapted to screw, the nut bearing against the outer face on the inner plate 19, as shown in Fig. 2.

The nut 27 is provided with a tubular barrel, in order to provide for the reception in this barrel of a lock generally designated at 28, of suitable type, having for instance the radial bolts 29 adapted to be extended outwardly at points inwardly beyond the flange 25 before mentioned, so as to prevent the nut 27 from being turned to release the clamping plates 19 and 20 when the parts are in operative position.

It is thus obvious that the inner adjacent ends of the several radial guard bars 10 are clamped with sufficient pressure to prevent their rotation with respect to the tubular adjusting members 12 before described, and that the means utilized for the purpose of clamping the bars 10 embody a single lock requiring but a single key for its release in order that the bars 10 may be readily withdrawn from the window frame after release of the clamping plates 19 and 20, by withdrawing the outer ends, carrying the stud fasteners 14 from the socket fastening members 15.

It is further obvious that by the particular arrangement on the socket fastening members 15, as before described, that is the fastening of the upper two thereof to the lower rail of the upper sash, the latter may be either secured in closed position, or in slightly lowered position providing for ventilation through the space above its upper end.

It is obvious that the spaces between the several guard bars 10 may be filled in by a suitable framework, or I preferably utilize for this purpose the radially outstanding arms 30, projecting outwardly between the several bars 10, and to the outer portions of which are secured laterally spaced connecting rings 31, between which the bars 10 pass so as to leave the latter free for adjustment in the manner before described. The inner ends of the arms 30 are preferably provided with reduced extensions 32, engaged between the clamping plates 19 and 20 in channels formed by recesses 33 and the flanges 21, similar to the recesses 22 before described.

To the outer ends of the arms 30 are also

secured the inner portions of suitable scrolls 34, extending outwardly between the rings 31 with their outer portions secured to the said rings 31 by clamps 35.

It is obvious however, that the particular framework between the bars 10 and the embellishment of the window guards in this way have artistic effect, and beauty and design may be varied within wide range, the essentials of the present invention being the use and means for this purpose including the radially projecting guard bars, the means by which the outer ends thereof are detachably held, and the clamping connections between their inner ends, including the lock 28, through the combined use of all of which the window guard is rendered practical, convenient, readily portable, and effective and efficient in use.

I claim:

1. In a window guard, a plurality of radial guard bars, detachable fastening members for the outer ends of said bars, and separable clamping means engaging the inner ends of said bars to normally prevent detachment of the outer ends thereof and key actuated locking means normally holding said clamping members in engaged position.

2. In a window guard, centrally disposed clamping means, guard bars extending radially from and having their inner ends engaged by the said clamping means, detachable fastening means at the outer ends of the guard bars, in connection with which the latter are held when the said clamping means are secured, and locking means normally holding the said clamping means in engaged position.

3. In a window guard, a plurality of radially disposed guard bars, detachable fastening means at the outer ends of said bars, and detachable clamping means connecting the inner ends of the several bars and including locking means normally holding the same in secured position.

4. In a window guard, a plurality of radially disposed guard bars, clamping means connecting the inner ends of said bars, and detachable connections at the outer ends of the bars, providing for their ready release when said clamping means are disengaged, and including socket fastening members and pivoted stud pieces carried by the guard bars for movement into and out of the said socket fasteners.

5. In a window guard, a plurality of radially disposed guard bars, clamping means connecting the inner ends of said bars, and detachable adjustable fastening means at the outer ends of the guard bars including tubular adjusting members into which the said outer ends of the guard bars are threaded.

6. In a window guard, a plurality of radi-

ally disposed guard bars, fastening means at the outer ends of the bars, and clamping means connecting the inner ends of said bars and including opposing separable clamping plates, one of which is provided with an internally threaded tubular portion projecting toward the other plate, a nut threaded into the said tubular extension on the clamping plate and bearing against the other plate so as to secure the said plates in clamped position.

7. In a window guard, a plurality of radially disposed guard bars, fastening means at the outer ends of the bars, and clamping

means connecting the inner ends of said bars 15 and including opposing separable clamping plates, one of which is provided with an internally threaded tubular portion projecting toward the other plate, a nut threaded into the said tubular extension on the clamping 20 plate and bearing against the other plate so as to secure the said plates in clamped position, said nut having a tubular barrel, a lock in the barrel of the nut having means to prevent the withdrawal of the nut from 25 the threaded tubular extension so as to thus lock the blades in clamped position.

HELEN S. CARSON.
